CHRISTMAS TREE ORNAMENT OR SIMILAR ARTICLE

Jack Burnbaum, 55 Lakeview Ave., Newton, Mass.

Filed Feb. 8, 1960, Ser. No. 59,305

Term of patent 14 years

(Cl. D29—1)

Fig. 1.

Fig. 2.

Fig. 3.

Fig. 1 is a top plan view of a Christmas tree ornament showing my new design,

Fig. 2 is a front elevational view thereof,

Fig. 3 is a side elevational view looking from the right or left of Fig. 1.

The design is characterized by having arms of different lengths extending from a central point, and a disc-like member surrounding said central point in the same axial plane as the four longer arms connected thereto, all as shown.

I claim:

The ornamental design for a Christmas tree ornament or similar article, substantially as shown and described.
